UNITED STATES PATENT OFFICE.

JOHN McMANAMY, OF GRAND RAPIDS, AND ANDREW REID, OF SAGINAW, MICHIGAN.

PUMP-GOVERNOR.

1,156,165.

Specification of Letters Patent. Patented Oct. 12, 1915.

Application filed April 20, 1914. Serial No. 833,120.

To all whom it may concern:

Be it known that we, JOHN McMANAMY and ANDREW REID, citizens of the United States of America, residing at Grand Rap-

5 ids and Saginaw, respectively, in the counties of Kent and Saginaw, respectively, and State of Michigan, have invented certain new and useful Improvements in Pump-Governors; and we do hereby declare the
10 following to be a full, clear, and exact description of the invention, such as will enable others skilled in the art to which it ap-
pertains to make and use the same.

This invention relates to improvements in
15 pump governors, and more particularly to governors to be applied to steam actuated air compressors for locomotives and automatically actuated by the air pressure produced by the said compressor, and its ob-
20 ject is to provide a device of this character which will be simple in construction and effective in operation, and to provide the same with various new and useful features as hereinafter more fully described and par-
25 ticularly pointed out in the claims.

As locomotives are commonly built, the air compressor is located at the side of the boiler directly in front of the cab and the ordinary type of pump governor is located
30 in the steam pressure pipe leading to the engine driving the compressor and a relief vent must be provided in the cylinder in which the valve actuating piston is located for the purpose of relieving the steam which
35 leaks to the under side of the piston. This type of governor is objectionable for various reasons: First, because the steam escap-
ing from the necessary vent will, especially in cold weather, cloud the windows of the
40 engine cab thus obscuring the view. At-
tempts have been made to overcome this difficulty by piping the exhaust from the vent away from the cab window but the steam in such pipe will condense and freeze
45 in cold weather and render the device in-
operative. Secondly, the necessary joints in the steam pressure line to insert a governor therein may become loose and leak, and fur-
thermore, if a governor between the engine
50 driving the compressor and the boiler should become inoperative it would be nec-
essary to close down the compressor while repairing the governor; and thirdly, the lubrication which is commonly fed to the
55 engine driving the compressor by being in-

jected into the steam before it enters the engine driving the pump will leak past the valve in the governor and a portion of it be lost through the vent therein.

The above objectionable features are ob-
viated by this invention in which the gov-
ernor is located in the exhaust from the com-
pressor engine and adapted to restrict the
same, thereby creating a back pressure which
slows or stops the operation of the engine,
60 hence the compressor, and located in this way
the governor may also be placed at a consid-
erable distance from the compressor engine,
and as the exhaust side thereof is open to
the atmosphere it is possible to provide an
65 interior vent passage through which the
steam from the under side of the valve op-
erating piston of the governor may escape
directly into the exhaust pipe.

The fact that the governor is on the ex-
haust side instead of the inlet side of the
compressor engine makes it possible to re-
move the governor for repairs and still op-
erate the compressor by temporarily con-
trolling the exhaust by a manually oper-
ated valve, and as the steam entering the
70 governor has already performed its func-
tion and the same has been utilized there is
no loss of the same by leakage in this de-
vice.

A preferred embodiment of our inven-
tion is illustrated in the accompanying
drawing which consists of a sectional view
of the governor in closed position, and also
one form of air control valve partially in
80 section which must be used to admit air
pressure to the governor to actuate the
same.

Like numbers refer to like parts.

1 represents the valve body having an
inlet 2 and an outlet 3 with a valve 4 of
the piston type interposed therebetween.
The valve stem 4 extends upward into a
cylinder 5 formed integral with the valve
body 1 and a piston 6 within said cylinder is
provided on the upper end of the stem. The
piston is normally raised by a spring 7 which
yieldably holds the valve open permitting
free passage therethrough.

The pipe 8 attached to the inlet side of
the governor leads from the exhaust side
of the compressor engine and the pipe 9 at
the outlet of the governor communicates
with the open air at any convenient point,
as for instance, on a locomotive it prefer-
105
110

ably communicates with the exhaust leading from the engine cylinders. A small passage 10 is provided in the partition of the valve body which passage provides a 5 constant communication between the two sides thereof, preventing an absolute closure of the passage therethrough and the valve 4 is tubular to near its upper end and a vent passage 11 is there provided which 10 communicates with the cylinder 5 beneath the piston 6 and with the interior of the valve 4, and when said valve is closed as illustrated this vent is in direct communication with the exhaust side of the gover- 15 nor.

The air pressure controlling valve 12 communicates with the cylinder 5 above the piston 6 and receives air under pressure produced by the air compressor through the 20 pipe 13. A valve 14 being yieldably closed by a spring 15 normally prevents admission of the compressed air to the cylinder 5, but when the air pressure which enters the valve 12 beneath a diaphragm 25 16 is sufficient to overcome the tension of the spring 15 the valve 14 will be raised, permitting the compressed air to flow into the cylinder to depress the piston 6 therein and close the valve 4. A small air vent passage 17 is provided beneath the valve 14, which allows the air to escape from the cylinder 5, this passage being so small that it will not prevent proper pressure on the piston 6 so long as the valve 14 is open, but 30 after the said valve is closed the pressure within the cylinder 5 will be gradually relieved, allowing the piston to rise and permit the valve 4 to open. This air control valve 14 forms no part of this invention 35 but is merely illustrated as the preferred means of admitting air to the cylinder 5 at the proper time and any other suitable form of control valve may be substituted with equally efficient results.

45 The operation of this device is as follows: Assuming the piston 6 to be raised and the valve 4 open, the exhaust from engine for the air pump passing through the pipe 8 will pass freely through the open valve and 50 be emitted through the outlet pipe 9. Under these conditions the compressor engine exhausts freely and drives the compressor to raise the air pressure in the tanks, etc., provided for it, but when the said pressure, communicating with the air control valve 12 through the pipe 13, is sufficient against the diaphragm 16, to compress the spring 15 and raise the valve 14, the compressed air is then admitted to the cylinder 5 above the piston 6 which forces it downward closing the valve 4. This immediately cuts off the exhaust passage from the engine except for the restricted passage 10, and a back pressure is created in the exhaust which prevents the operation of the

70 engine except very slowly as the exhaust escapes through the said passage 10. The purpose of this small passage and slow operation of the engine is to prevent condensation of steam in the pipe, which would result were the engine to stop entirely. With the valve thus closed the pressure on the inlet side of the governor will cause some steam to leak past the valve stem 4^a 75 into the cylinder 5 beneath the piston 6 and the steam thus entering the cylinder, as well as any leakage past the piston from the upper end of the cylinder, will escape through the vent 11 and thence into the exhaust side of the governor and out through 80 the pipe 9 without being vented into the open air directly at the governor.

When the air pressure in the system is lowered the tension of the spring 15 will be sufficient to again close the valve 14 and 85 the compressed air in the cylinder 5 will then be relieved through the small air vent 17, allowing the piston 6 to rise by action of the spring 7 and open the valve 4, thus permitting the engine to again operate the 90 compressor to bring the air pressure up to the maximum whereat the governor will repeat the above described operation.

What we claim is:—

1. The method of controlling an air compressor engine, consisting of interposing a throttle valve in the exhaust of the same and providing automatic means for adjusting the valve to restrict the exhaust from the compressor engine as the air pressure 100 produced by the compressor is increased.

2. In combination with an air compressor engine, a throttle valve arranged in the exhaust passage of the same, and means for automatically closing said valve operated by air pressure produced by the compressor. 105

3. A compressor governor, comprising a throttle valve arranged in the exhaust passage of the compressor engine, a cylinder and piston to adjust the valve, means for admitting pressure to the piston to close the throttle, a spring to open the throttle and a vent opening between the cylinder and the outlet side of the throttle. 110

4. A compressor governor, comprising a throttle valve arranged in the exhaust passage of the compressor engine, a cylinder and piston to adjust the valve, means for automatically admitting pressure to the cylinder above the piston to close the throttle, a spring to open the throttle, and a vent opening communicating with the cylinder beneath the piston and with the outlet side of the throttle. 115

5. A compressor governor, comprising a throttle valve arranged in the exhaust passage of the compressor engine, a cylinder in axial alignment with said valve, a valve stem projecting into said cylinder, said valve 120

and stem being axially chambered and said chamber opening through the lower end of the valve and communicating with the exhaust side of the throttle when the valve is closed, a piston in said cylinder attached to the upper end of said stem, means for automatically admitting pressure to the upper side of the piston to close the valve, a spring to open the valve and a vent opening in the valve stem communicating with

the cylinder beneath the piston and with the said chamber in the stem.

In testimony whereof we affix our signatures in presence of two witnesses.

JOHN McMANAMY.
ANDREW REID.
